UNITED STATES PATENT OFFICE.

NATHANIEL BALDWIN, OF EAST MILL CREEK, UTAH.

TELEPHONE RECEIVER.

Application filed August 29, 1925. Serial No. 53,350.

The present invention appertains to telephone receivers and embodies a general principle disclosed in my former Patent No. 957,403, issued May 10, 1910, namely, the 5 principle of using an armature actuated by a surrounding coil or coils and acted upon at its ends by four polepiece limbs arranged alternately on opposite sides of the armature as illustrated in Fig. 13 of the above mentioned 10 patent.

The objects of the present invention are to provide a convenient arrangement and magnetic connection of such polepieces. To provide suitable resilient supports for the armature and suitable means to transmit the movements of the armature to a diaphragm or other sound producing agent or element.

I attain these and other objects by the mechanism illustrated in the accompanying 20 drawing in which Fig. 1 is a back view of the instrument with part of the shell cut away; Fig. 2 is a section of the instrument along the line AB of Fig. 1; and Fig. 3 is a partial section of the instrument along the line CD of 25 Fig. 1, showing parts in elevation with one magnet removed.

In the several figures of the drawing numeral 1 designates a baseplate to which the magnets 2 and 3 are secured by means of 30 screws, solder or otherwise. These magnets are substantially semicircular in shape with abutting ends straightened to fit the polepieces 4 and 5 which are secured to the magnet by means of screws as shown.

The spool 6 is a structure similar to that shown in my former patent but has no fulcrum provided in it. It is inclosed and held in position by the polepieces 4 and 5. These polepieces are formed by bending flat bars of 40 iron into U-shaped pieces and cutting away the upper part of one limb and the lower part of the other. The polepieces then fit together over the spool and projecting edges 7, 7 and 8, 8 formed on the limbs of the polepieces engage the straight edges of the spool 6 and hold it in proper position, and the proper spacing between the polepieces is also maintained.

The terminals of the coil which is wound 50 upon the spool are connected to the cord tips 10, 11, by means of binding posts or connections of any convenient design.

A shell or casing 12 incloses these several 55 parts and the base plate 1 is held upon the casing 12 by means of the clamping ring 14. An armature 15 passes through the aperture

in the spool 6 and between the limbs of the polepieces 4 and 5 without touching either and is supported in proper position within the spool 6 and between the limbs of the polepieces 4 and 5 by means of small strings or wires 16, 16 which pass through slots in the ends of the armature 15 and are held taut by brackets 17, 17 to which the ends of the strings or wires 16, 16 are secured. The 60 brackets 17, 17 which may be secured to one or both of the polepieces 4 and 5 are slotted near one end as shown and screws 18, 18 tapped into the brackets are adapted to spread the slots more or less and thus adjust 65 the tension of the strings or wires 16, 16.

The diaphragm 13, which is made rigid by a special shape is supported from the armature 15 by the connecting rods 19 and vibrates as a whole in connection with the armature. 70

I claim—

1. A telephone receiver comprising an armature mounted on tensioned members, and adapted to vibrate transversely, an actuating coil disposed around said armature, a diaphragm and means to transmit the motion of said armature to said diaphragm, a diaphragm carried by said armature.

2. A telephone receiver comprising an armature mounted on tensioned members, and adapted to vibrate transversely, an actuating coil disposed around said armature, a diaphragm and connecting rods to transmit the motion of said armature to said diaphragm.

3. A telephone receiver comprising an armature mounted on tensioned members, and adapted to vibrate transversely, an actuating coil disposed around said armature, four polepiece limbs acting upon the ends of said armature, two polepiece limbs of like polarity 95 acting upon opposite ends and upon opposite sides of said armature and the other two polepiece limbs of opposite polarity from the first mentioned polepiece limbs acting upon the said armature in alternate positions to the 100 first mentioned polepiece limbs, a diaphragm and connecting rods to transmit the motion of said armature to said diaphragm.

4. A telephone receiver comprising an armature, surrounded by an actuating coil 105 and adapted to vibrate transversely, stretched members resiliently supporting said armature, a diaphragm and connecting rods to transmit the motion of said armature to said diaphragm.

5. A telephone receiver comprising an armature surrounded by an actuating coil,

and adapted to vibrate transversely, stretched members resiliently supporting said armature, four polepiece limbs acting upon the ends of said armature, two polepiece limbs 5 of like polarity acting upon opposite ends and upon opposite sides of said armature and the other two polepiece limbs of opposite polarity from the first mentioned polepiece limbs acting upon the said armature in alternate 10 positions to the first mentioned polepiece limbs, a diaphragm and connecting rods to transmit the motion of said armature to said diaphragm.

6. A telephone receiver comprising an 15 armature resiliently supported, surrounded by an actuating coil and adapted to vibrate transversely, connecting rods, a diaphragm mounted upon said armature by means of said connecting rods and adapted to vibrate with 20 said armature.

7. A telephone receiver comprising an 25 armature surrounded by an actuating coil and adapted to vibrate transversely, stretched wires resiliently supporting said armature, connecting rods, a diaphragm mounted upon

said armature by means of said connecting rods and adapted to vibrate with said armature.

8. A telephone receiver comprising an 30 armature surrounded by an actuating coil, stretched wires resiliently supporting said armature, four polepiece limbs acting upon the ends of said armature, two polepiece limbs of like polarity acting upon opposite ends and upon 35 opposite sides of said armature and the other two polepiece limbs of opposite polarity from the first mentioned polepiece limbs acting upon the said armature in alternate positions to the first mentioned polepiece limbs, connecting rods, a diaphragm mounted upon said armature by means of said connecting rods and adapted to vibrate with said armature.

9. In combination an armature, tensioned 40 resilient supporting means whereon said armature is mounted, an actuating coil disposed around said armature, a diaphragm, and means to connect said armature to said diaphragm.

NATHANIEL BALDWIN.
